EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

MULTIPLE-DISK BRAKE.

1,351,006.

Specification of Letters Patent. Patented Aug. 24, 1920.

Application filed September 10, 1918. Serial No. 253,458.

To all whom it may concern:

Be it known that I, EUGÈNE SCHNEIDER, a citizen of the French Republic, and a resident of 42 Rue d'Anjou, Paris, France, 5 have invented a new and useful Improvement in or Relating to Multiple-Disk Brakes, which invention is fully set forth in the following specification.

This invention relates to brake mechanism of the type commonly called "multiple-disk brakes", and it has for its object to provide brake mechanism of this character of improved construction whereby, among other things, the wear of the disks 15 is reduced and the inspection and overhauling of the brake are facilitated.

Heretofore this type of brake has comprised an assemblage of two series of annular disks, the disks of one series being connected at their inner peripheries so as to rotate together, while the disks of the other series were similarly connected at their outer peripheries. Thus, the former series of disks have been connected to a shaft or a 25 sleeve thereon, so as to rotate therewith, by projections on the disks entering grooves in the shaft or sleeve, and the latter series of disks have been similarly connected to an exterior drum by projections on the disks 30 entering corresponding grooves in the drum. The disks have been pressed together in any suitable manner as by the action of the load on a pinion on said shaft and the action of the motor on a wheel the nave of which has 35 helicoidal faces engaging like faces on a sleeve sliding on said shaft and contacting said disks. In these structures, the drum has been held, while the load descends, by a suitable pawl and ratchet mechanism.

40 Whatever may be the details of construction of this kind of brake, it has always included a drum which turned, at least during the raising of the load, and which inclosed the whole system of disks. The metallic 45 mud produced by the wear of the disks, owing to their rubbing against each other, collected in the lubricating oil bath contained in the lower part of the drum, and since the turning of the drum stirred up this 50 mud, the wear of the disks by the metallic particles suspended in the oil has been much aggravated. Moreover, the disks could not be inspected while the brake was in use, or

handled without completely dismounting the parts.

60 The present invention avoids these drawbacks. To this end, one set of disks is rendered independent of the drum by connecting them directly with each other by interlocking projections so that there may be 65 substituted for the rotary drum a casing which is normally stationary. The mud, which can thus settle readily in the casing may be withdrawn easily through a cleansing cock preferably provided at the lowest 70 part of an inclined bottom in the casing. The casing is also preferably made in two parts fitting together in a horizontal plane so that the upper part can be removed for inspection of the disks even while the brake 75 is at work.

80 The invention is capable of receiving a variety of mechanical expressions, one of which is shown on the accompanying drawings, but it is to be expressly understood that 80 the drawings are for purpose of illustration only, and are not to be construed as a definition of the limits of the invention, reference being made to the appended claims for that purpose.

85 Said drawings illustrate the invention embodied in a brake mechanism in which pressure is applied by both a screw and springs, a safety release being also provided in case the motor should refuse to operate 90 for the descent of the load.

Figure 1 is an axial section through the brake. the upper half of the casing being shown in elevation;

Fig. 2 is half a cross section on line II— 95 II of Fig. 1; and

Fig. 3 shows a developed periphery of the disks.

As with brakes heretofore in use, the new 100 brake comprises two series of disks A, B. The construction illustrated is of a well-known type of brake and comprises a reversible screw on the shaft, with respect to 105 which the sleeve M is displaceable, and resilient means, as Belleville washers, which constantly tend to press the disks B on the disks A and thereby, by the friction developed between said disks, through the application of the braking resistance to the shaft C, oppose the motor running away 110 when without load. The disks A are made

in the usual manner and suitably engaged with the shaft C or the sleeve M, as by projections *a* which enter a longitudinal groove *c* in the shaft or sleeve.

5 According to this invention, the disks B, which alternate with the disks A and are free on the shaft C, are connected together as follows:—

Each disk B has projecting from the 10 outer periphery of one or both of its faces subjected to friction, teeth or projections B', which may be made by cutting away portions of a cylindrical flange on the disk. Between these teeth are spaces B² of a 15 length which may vary but which is at least equal to that of a tooth. The teeth B' of each disk B engage in the spaces B² of two neighboring disks, thus locking these disks together at their lateral faces but outside 20 the outer periphery of the disks A. It is preferable that the periphery of the disks A should not be completely covered by the teeth of disks B; accordingly, as here shown, the spaces B² are made longer than the teeth 25 B'. This is done for the purpose of facilitating lubrication by means of the ducts I which receive and deliver lubricant through the spaces between the teeth.

The disks B being thus interlocked, the 30 friction to which they give rise at their faces during the descent of the load is balanced by any suitable device as by a toothed ring or, as here shown, a coupling with helicoidal inclines locking in its revolution and 35 a conical coupling. A sleeve J, mounted free on the shaft C, is provided with lateral peripheral teeth J' which interlock with the corresponding teeth on the last disk B in a manner similar to that in which the 40 disks B are interlocked. This sleeve has helicoidal inclines *j* coacting with corresponding inclines *k* carried by a sleeve K the outer periphery *k*¹ of which is coned to the same conicity as that of the inner 45 surface D' of the casing D. This holding device, however, may be applied to any of the disks B instead of to the last of the series.

A load being suitably connected with a pinion (not shown) on the right-hand end 50 of the shaft C, and said pinion rotating anti-clockwise when looking from right to left in Fig. 1, suppose the motor to be stopped. The disks A and B are pressed together under the influence of the weight 55 of the load and by the effect of the helicoidal inclines *j*, *k*, and this pressure increases until the friction developed is sufficient to balance the load, which is thus suspended without exerting any force on the motor 60 pinion F, because the reaction is taken up by the conical surfaces *k*¹, D¹.

If it is desired to lower the load, it is only necessary to exert on the motor pinion F, in an anti-clockwise direction, a force sufficient 65 to overcome the friction between the disks

A and B. Thereupon, the disks A, B, are freed, owing to the decrease in friction therebetween, and the load drives the shaft C and effects descent as long as a sufficient force is exerted on the pinion F.

If it is desired to raise the load, the motor pinion F is rotated in a clockwise direction, looking from right to left in Fig. 1. Thus a tendency is created to press the 75 disks A and B together by screwing the sleeve M on the screw formed at the end of the shaft C, but the helicoidal inclines *j*, *k*, are now freed as well as the conical surfaces *k*¹, D¹, and the pinion F, shaft C and disks A, B, turn as if they were a unit.

The form of the interlocking teeth B' may be modified without departing from the invention; thus they may be made unsymmetrical or they may project from only one side of each disk. This method of connecting the disks B is also applicable to any other construction of multiple disk brake in which the functions of the disks B and A are reversed in the sense that the disks A, which are operatively connected at their 85 inner peripheries, are held from movement during the descent of the load.

As shown in Figs. 1 and 2, the casing D normally held stationary, as by a band brake L, has, in accordance with the invention, a 95 bottom surface D² sloping toward a cleaning vent d². The casing D can be dismounted, and for this purpose it is divided along a horizontal axial plane so that by lifting the upper part D³ all the disks A, B can be inspected, even while the brake is in operation.

While the embodiment illustrated on the drawing has been described with considerable particularity, it is to be understood that the invention is not to be restricted thereto, 105 as the same is capable of receiving a variety of mechanical expressions, some of which will readily suggest themselves to those skilled in the art, while certain features thereof are capable of use without other features thereof. Reference is therefore to be had to the appended claims for a definition 110 of the limits of the invention.

What is claimed is:—

1. In a multiple disk brake, a shaft, a 115 series of disks operatively connected therewith, a second series of disks alternating with the disks of said first series, interlocking peripheral projections on the disks of said second series, and a relatively stationary casing for said disks separate therefrom.

2. In a multiple disk brake, a shaft, a series of disks operatively connected therewith, a second series of disks alternating with the disks of said first series, and interlocking, peripheral, arcuate flanges on the 120 disks of said second series.

3. In a multiple disk brake, a shaft, a series of disks operatively connected therewith, a second series of disks alternating 130

with the disks of said first series, and interlocking projections on the peripheries of the disks of said second series, the distance between successive projections being greater than the circumferential length of such projections.

4. In a multiple disk brake, a shaft, a series of disks operatively connected therewith, a second series of disks alternating with the disks of said first series, interlocking projections on the peripheries of the disks of said second series spaced by distances greater than the circumferential length of said projections, lubricating ducts in the faces of said disks and communicating with the spaces between said projections, and a relatively-stationary casing separate from said disks and containing an oil bath therefor.
5. In a multiple disk brake, a shaft, a series of disks operatively connected therewith, a second series of disks alternating

with the disks of said first series, interlocking peripheral projections on the disks of said second series, a relatively stationary casing separate from said disks and containing an oil bath therefor, said casing having an inclined bottom, and a cleaning opening at the lower end of said incline.

6. In a multiple disk brake, a shaft, a series of disks operatively connected therewith, a second series of disks alternating with the disks of said first series, peripheral projections on each of the disks of said second series, said projections interlocking, and a relatively stationary casing for said disks separate therefrom and containing an oil bath therefor.

In testimony whereof I have signed this specification.

EUGÈNE SCHNEIDER.
